ELECTRONIC COUNTING CIRCUIT

Ernest Oliver Holland, Cambridge, England, assignor to Pye Limited, Cambridge, England, a British company

Application August 30, 1949, Serial No. 113,125
In Great Britain August 31, 1948

1 Claim. (Cl. 250—27)

1

The present invention relates to an electronic counting circuit of the resistance-coupled multivibrator type, which is particularly suitable for use in a binary system of counting.

The principles of electronic counting using resistance-coupled multivibrators are described in an article entitled "Electronic counters" by I. E. Grosdoff in the September 1946 edition of "R. C. A. Review" published by the Radio Corporation of America, Princeton, New Jersey, U. S. A.

With the multivibrator circuit arrangements there described, however, variations in the output from the valve anode consequent upon variations in the load affect the triggering of the valves and experiments have shown that these variations cause instability with resultant inaccuracies in the counting.

The present invention has for its object to provide a resistance-coupled multivibrator circuit for electronic counting which is stable in operation and, to this end, consists in incorporating multi-grid valves in the multivibrator and connecting the output and input circuits to separate electrodes of the valves.

In the preferred form of the invention, the multivibrator comprises a pair of pentode valves of which the anodes and control grids are cross-connected, the input triggering signals being fed to the anodes and the output signals being taken from the screening grids of the two valves.

The preferred circuit arrangement is illustrated in the accompanying drawing, in which V_1 and V_2 comprise two pentode valves, the anodes A_1A_2 of the two valves being cross-connected respectively to the control grid G_1G_2 of the other valve through the resistance capacity networks R_1C_1 , R_2C_2 respectively. The control grids G_1G_2 are also connected to the negative high tension lead or earth potential through the resistors R_3R_4 respectively. The anodes of the two valves are connected through resistors R_5R_6 to the point I to which the input signals are fed, the point I being connected to the high tension positive supply lead through the resistance R_7 . The suppressor grids P_1P_2 of the two valves are connected to their respective cathodes C_1C_2 which are commoned and connected to the high tension negative lead through the resistance R_8 shunted by the condenser C_3 . The outputs from the two valves are taken from the screening grids S_1S_2 respectively through the condensers C_4C_5 . The screening grids are maintained at the desired positive potential through the voltage dropping resistors R_9R_{10} connected to the high tension positive supply lead.

2

The multivibrator is triggered by the application of negative pulses to the point I, each negative pulse causing the valves to switch over alternately from the conducting to the non-conducting condition and vice versa in the manner common to multivibrator circuits. As each change-over occurs, an output signal appears alternately in the output circuits connected to the screen grids of the two valves. Thus, if the output from one of the screen grids is considered, one pulse is produced in this output circuit for each two negative pulses which are applied to the input I. Thus, the system effects a division by two according to the binary system. The connection of the output circuit to the screen grid, however, separates the output circuit from the input circuit so that any variations in the output load do not affect the stable operation of the arrangement and accurate counting can be obtained. With the circuit described, the valve of the resistance R_8 is not critical as in previously known counting circuits.

The use of a multi-grid valve also reduces inter-electrode capacities and, due to the additional gain and greater slope of the valve, the build-up time of the pulses is shorter which consequently results in more abrupt change over from one valve to the other.

A plurality of units as described may be connected in series for effecting higher counts, and the pulses from a later stage may be fed back to a preceding stage in the manner described in the aforesaid publication in order to obtain a desired count which may not be a multiple of two.

While a particular embodiment has been described, it will be understood that various modifications may be made without departing from the spirit of the invention. For example, the input pulses may be applied to the suppressor grid, or a hexode or heptode valve may be used instead of a pentode. When using hexodes or heptodes, the second mixing electrodes may be joined together and the triggering pulses injected there.

In a modification, the arrangement may be used for a symmetric operation by connecting the resistances R_5 and R_6 direct to the high tension supply lead instead of through the common resistor R_7 , and applying separate triggering pulses directly to the anodes of the two valves. The valves may then be alternately switched on and off in accordance with the application of the negative pulses to one or other of the anodes.

55 I claim:

A binary electronic counting circuit compris-

ing a pair of pentode valves arranged in a trigger-pair circuit, means comprising a resistor connecting the anode of each valve to a high tension positive supply, means comprising a resistance shunted by a capacity connecting each anode to the grid nearest to the cathode in the other valve, means connecting the suppressor grid in each valve to the cathode of that valve, means for applying the pulses to be counted to the anodes of both of the valves simultaneously and means for deriving the output pulses from the screen grid of one of the valves, said screen grid being connected to the high tension positive supply through a resistor.

ERNEST OLIVER HOLLAND.
